(57) **CLAIM**

The ornamental design for a wide faceted slotted ground jaw, as shown and described.

DESCRIPTION

FIG. 1 is a perspective view of a wide faceted slotted ground jaw showing my design, the tubing sealer shown in dashed lines is included as part of the environment of my invention and forms no part of the claimed design;

FIG. 2 is a top front right view thereof;

FIG. 3 is a top rear left view thereof;

FIG. 4 is a top plan view thereof;

FIG. 5 is a front elevational view thereof;

FIG. 6 is a rear elevational view thereof;

FIG. 7 is a bottom plan view thereof; and

FIG. 8 is a right side elevational view thereof; and,

FIG. 9 is a left side elevational view thereof.
